INTERMITTENT LIGHTING MEANS FOR
MOTION PICTURES

William E. Celestin, New York, N. Y.

Application February 18, 1949, Serial No. 77,220

2 Claims. (CL 88—17)

1

My invention relates particularly to a lighting apparatus for providing more effective lighting in projecting motion pictures.

In previous lighting apparatus, as for instance that used in the projection of theatrical motion pictures, there are many inadequacies, among which the most important are the excessive heat generated by the crater of the carbon arc, the fire hazard from the open flame of the gas ball of the carbon arc, the difficulty of maintaining uniform luminosity and screen brilliance for any length of time, and the great loss of the light generated in the lamp house of the projector which does not reach the screen.

In accordance with my invention, these disadvantages are effectively overcome, continual watching of the light source is no longer necessary, and, besides, a more uniform light and control thereof is obtainable and the fire hazard is eliminated. In fact, the operation thereof is substantially automatic. Further objects of my invention will be seen from the detailed description thereof, hereinafter.

I accomplish this, preferably, by utilizing an evacuated, hollow, vitrious gas envelope containing an inert gas, such as krypton, helium, xenon, argon, or other similar noble gaseous filling. This is in the form of a cathode discharge lamp giving instantaneous flashes of light of high intensity synchronized with the pull-down movement and shutter of the projecting machine.

While my invention is capable of embodiment in many different forms, for the purpose of illustration I have shown only one form thereof in the accompanying drawings, in which—

Fig. 1 is a diagrammatical vertical section of a projecting machine made in accordance with my invention;

Fig. 2 is a diagrammatic illustration of the electrical circuit used together with a vertical section of the light source shown in Fig. 1;

Fig. 3 is a fragmental enlarged side elevation of the said light source, showing the light bulb wheel, taken on a plane at right angles to the axis thereof;

Fig. 4 is a fragmental enlarged radial section of said wheel; and

Fig. 5 is an enlarged detail of the shutter gearing.

In the drawings, I have shown a casing 1 hav-

2

ing on the top thereof a circular casing 2 for a film reel 3, carrying therein a film 4 to be exhibited, the reel 3 being carried on a central pivot 5, in the usual way. The film 4 is fed downwardly by a sprocket 6 against which two small idlers 7 and 8 are spring pressed by a frame 9, in which they are carried, pivoted on a shaft 10 carried by the casing 1. The film then passes between a pair of idler rolls 11 and 12 pivoted in the casing 1, thence through front and rear gates 13 and 14 having rectangular openings 15 and 16 for the passage of the light. Thence the film 4 passes downwardly over idler rollers 16 and 17 and onto a sprocket 18 onto which it is pressed by idlers 19 and 20 on a frame 21 carried by a shaft 22 on the casing. From this point the film 4 passes onto a lower reel 23 pivotally supported in the casing 1 in the usual way.

For driving the mechanism, there is provided an A. C. motor 24 having leads 25 and 26 leading to the usual house circuit and having a switch 27 in a switch housing 28, for turning the current to the motor 24 on and off, as desired. The motor 24 has a driving shaft 29, which may have any usual suitable gearing connected to the sprockets 6 and 18 for driving the same in the usual way, not shown. On the shaft 29, furthermore, there is a gear 30 which drives a gear 31 on a shaft 32 carrying a clutch disc 33 to cooperate with another clutch disc 34 splined on a shaft 35 and having the usual clutch lever 36 for throwing the clutch 33, 34 into and out of engagement at will. On the shaft 35 there is a worm wheel 37 for driving a worm 38 having a radial pin or arm 39 which engages with a pin 40 in an arm 41 having one or more teeth or prongs 42 to engage the usual film perforations, as in the case of the usual pull down mechanism, for advancing the film one frame at a time. The lower end of the arm 41 is normally pressed upwardly by a link 43 carried loosely on a fixed stub shaft 44 on the casing 1, and carrying a spring 45 having its end attached, respectively, to the link 43 and the shaft 44. The worm wheel 38 is on a shaft 46 journaled in the casing 1, and near one end thereof has a sprocket 47 for driving a sprocket belt 47a carried by a small sprocket 48 on a slide peripherally grooved shaft 49, on which it has a spline 49b for relative movement of the shaft 49, 50 which is supported so as to cooperate with a re-

taining ring having a spring pressed ball 49a in a lamp house 50, having four or more ventilation openings 51. The shaft 49 has operating handles 52 and 53 at the end thereof so as to move one or the other of two light bulb wheels 54 and 55, tight on the shaft 49, into position before a conical reflecting light exit 56, located in the bulb housing 50, which registers with the usual cylindrical condenser 57 having one or more condensing lenses 58 to produce parallel light beams to be projected through the film 4 while at rest between the gate openings 15 and 16, and thence through any desired shutter 59, on a shaft 60 carrying a driving worm 61, which is located in the rear of an objective 62 of any desired type. The shutter shaft 61 is driven in timed relation to the pull down mechanism 41 through the motor from the shaft 46 by a worm 63 on the shaft 46, or any suitable gearing connection, it being immaterial how the gears are arranged providing the speed of the shutter and pull down are properly synchronized.

Each of the bulb wheels 54 and 55 is constructed like the other except that the brush contacts are on opposite sides thereof, respectively. Consequently, only one of them, the wheel 54, will be described in detail, as shown in Figs. 3 and 4. The wheel 54 is comprised of an outer disc 64 carrying two sets of radial contact plates 65 and 66 of metal separated from each other, which contact, respectively, with brushes 67 and 68, like similar brushes 69 and 70 cooperating with like sets 71 and 72 on the wheel 55. All these brushes 67, 68, 69 and 70 are mounted on a slideable insulating flat base 73 having an arm loose on the shaft 49, to cooperate with two stationary contacts 73a and 73b in the housing 50. The wheel 54, furthermore, has an inner disc 74, on the shaft 49, secured by a circular parabolic reflector 75 to the outer disc 64 on which the contacts 65 and 66 are carried. Between the two discs 74 and 64 there are secured, on the disc 64 a plurality of pairs of metal U-shaped clips 77 and 78, for instance about twelve such pairs, although any other number can be provided. The inner clips 77 are connected to the contacts 65, respectively, by conducting rivets 79 and the outer clips 78 are connected to the conducting plates 66, respectively, by conducting rivets 80.

Each pair of clips 77 and 78 carries therein a cylindrical glass or quartz tube 81 containing one or more of the rare gases, such for instance as one or more of those rare elements obtained from the air, for example krypton or krypton and xenon. The tube has cylindrical conducting terminals 82 and 83 on the ends thereof within the clips 77 and 78, said terminals being connected to an anode and cathode, respectively, within the bulb 81 to carry the current therefrom through the body of gas which is at any desired vacuum or pressure within the bulb 81, for instance 1 to 2 centimeters of mercury. The gas contains krypton and preferably carries a proportion, comprising any desired amount, of xenon. These bulbs or envelopes can produce flashes of the most intense of all known types of light, for a fraction of a second at least, once their conductivity is established by ionizing the gas with the initial voltage passed through the same. Preferably this initial voltage may be 2000 volts or even higher, after which the gas therein presents substantially no resistance to the further passage of the current therethrough. The gearing 47, 48 is so arranged that there is a flash from

one of the bulbs 81 during the time that the film 4 is at rest for projecting one of the frame pictures therefrom and in the time when the next frame picture is being exhibited the next one of the bulbs 81 is being energized. However, sufficient time is allowed to elapse for the build up to the initial high voltage after the closing of the brush contacts 67 and 68 for the particular bulb 81, before said bulb 81 is located opposite the conical reflector 56, when the particular film frame is at rest to be exhibited, but as the said flash is extremely short the flash can take place at any time or portion thereof while the film is at rest for the particular frame being projected.

For this purpose, there is provided a connection to the usual house A. C. circuit, or a wet or dry storage battery, by wires 84 and 85 leading to a coil 86 of one or a number of transformers to step up the voltage by means of a coil 87 in a circuit 88 leading to one or more bulb rectifiers 89 having two wires 90 and 91 to deliver the direct current to one or a series of condensers 92 of any desired size and number of plates, the two sides of which are connected, respectively, by wires 83 and 94, to the brushes 68, 70 and 67, 69. As a result, voltages of 2000 to 6000 will accumulate in the condensers or capacitors 92 until this charge is discharged through the particular bulb 81, while the shutter opening is opposite to the film frame being projected. The electrical energy then rushes at a high speed through the gas in the bulb 81. The bulb in this way is capable of at least 10,000 of these short duration flashes of from $1/100$ to $1/1,000,000$ of a second, after which any one or more of the bulbs can be readily replaced by removing it from the clips 77 and 78 and inserting a new bulb instead. Also, the bulb wheels 54 and 55 can be moved to interchange their positions so as not to lose time in replacements of the bulbs and so as to give better access thereto for repairs, etc., and while the films are being replaced.

While I have described my invention above in detail it will be understood that many changes may be made therein without departing from the spirit of my invention.

I claim:

1. A light source of high intensity adapted for lighting in cinematography, comprising a plurality of sets of radially arranged high intensity flash bulbs containing a gas adapted to be rendered incandescent, a rotatable mounting for the said sets of bulbs having an axially displaceable axis for said sets as well as a mechanism for advancing said sets of bulbs upon the rotation of the mounting, and an electrical means for energizing the bulbs of a set selected by said displacement successively without energizing the bulbs of another set upon the rotating of said mounting, having a circuit closing device which closes the circuits of the bulbs in succession.

2. In combination, a light source of high intensity adapted for lighting in cinematography, comprising a plurality of sets of radially arranged high intensity flash bulbs containing krypton, a rotatable mounting for the said sets of bulbs having an axially displaceable axis for said sets as well as a mechanism for advancing said sets of bulbs upon the rotation of the mounting, an electrical means for energizing the bulbs of a set selected by said displacement successively without energizing the bulbs of another set upon the rotating of the mounting, having a circuit closing device which closes the circuits of the bulbs

in succession, and a motion picture apparatus having a reciprocating pull down mechanism geared to the mechanism for advancing the bulbs for intermittently advancing the film to successive light-receiving positions synchronously connected for movement with the first mentioned mechanism and with the circuit closing device.

WILLIAM E. CELESTIN.
